DESIGN FOR A TAPE SERVING MACHINE

Theodore H. Krueger, Stratford, Conn., assignor
to Better Packages Incorporated, a corporation
of New York

Application January 29, 1941, Serial No. 98,495

Term of patent 14 years

To all whom it may concern:

Be it known that I, Theodore H. Krueger, a citizen of the United States, residing in Stratford, county of Fairfield and State of Connecticut, have invented a new, original, and ornamental Design for Tape Serving Machines, of which the following is a specification, reference being had to the accompanying drawing, forming part thereof.

The figure is a perspective view of a tape serving machine showing my new design, the opposite side and end not shown are substantially plain.

I claim:

The ornamental design for a tape serving machine, substantially as shown and described.

THEODORE H. KRUEGER.
